Inventor:
Charles D. White

By C. A. Mason Atty.

UNITED STATES PATENT OFFICE.

CHARLES D. WHITE, OF NORWICH, CONNECTICUT.

PROTECTOR FOR SPINNING RINGS.

Application filed November 10, 1922. Serial No. 600,111.

To all whom it may concern:

Be it known that I, CHARLES D. WHITE, citizen of the United States of America, residing at Norwich, in the county of New London and State of Connecticut, have invented a certain new and useful Protector for Spinning Rings, of which the following is a full, clear, and exact description.

This invention relates to protectors for spinning rings and more particularly to means for guarding the ring and its traveller from the accumulation of foreign matter such as lint, etc.

The invention comprises a protector of the type referred to which is made of pressed steel or other thin metal. The protector is so constructed as to extend upward from the base of the holder of the ring and partially surrounds the latter at a height which will be sufficient to prevent the accumulation of lint, or other foreign matter on the traveller.

As an incident of the construction also the deposit of lint on one traveller, which lint is thrown off from an adjacent traveller is effectually prevented.

These and other features and advantages of the invention will be more clearly apparent from the following description in connection with the accompanying drawings, and the novel features will be pointed out in the appended claims:

Referring to the drawings:

Fig. 1 represents in plan view a spinning ring having applied thereto a device embodying the invention;

Fig. 2 is a front elevation, and

Fig. 3 is a section on the line 3—3, Fig. 1.

A portion of the ring rail 3 supports a spinning ring holder 5, the latter provided with the usual slots 6, preferably at diametrically opposite points, to receive screws 7 which clamp the holder to the ring rail. The holder is provided with the usual upstanding bent portions 9 for engaging the base flange 11 of the ring 12, which latter is provided with the usual traveller, as 14.

The guard or protector 15 is herein made in the form of an upstanding piece of thin metal, as pressed steel, provided with a base

flange 16 resting upon the ring holder 5 and suitably secured thereto, as by soldering. The protector 15 extends upwardly a suitable distance above the ring and the traveller thereon, and is arranged in parallelism with the ring and extends around the same a substantial distance leaving an opening 18 at the front portion of the rail for the escape of such lint, or other foreign matter as may have been deposited upon the traveller, the rapid rotation of the latter causing any such matter to be ejected through said opening.

The protector 15 is so designed, and is so located with reference to the ring and traveller, as to prevent the accumulation of lint on the traveller, and especially does it act to guard the traveller of each individual spinning ring against such lint as may be thrown off from the traveller of an adjacent ring. While it is possible, of course, that some small amount may settle from above on the traveller, this will be ejected through the opening 18 by the traveller as it rotates on the ring, and the lint will thus be prevented from accumulating to an extent to interfere with the free operation of the traveller and cause the breakage of threads.

Being constructed of thin sheet steel or other sheet metal, this protector is especially adapted for use in each individual ring of the frame, and when mounted upon the ring holder the protector constitutes, with such ring and holder, a unit which is readily applicable in its entirety to the ring rail, and at the same time is capable of removal therefrom as an entirety also.

Having thus described my invention, what I claim as new and desire to secure by U. S. Letters Patent is:

1. A device of the class described, comprising in combination with a spinning ring and its holder, an upstanding protector of sheet material extending circumferentially of the ring for a substantial distance and having its ends spaced to form an opening for the ejection of lint.

2. In a device of the class described, the combination with a spinning ring and traveller, of a protector arranged to partially

surround said parts, and having an opening at the front thereof, said protector extending above the ring and traveller.

3. In a device of the class described, the combination with a ring holder, of a spinning ring thereon, and a protector of sheet metal secured to the holder and extending upwardly above the ring, said protector en-

closing a substantial portion of the ring and provided with a relatively small opening between its ends for the exit of lint.

In testimony whereof I have hereunto set my hand this first day of November, A. D. 1922.

CHARLES D. WHITE.
